PORTATIVE INTERNAL COMBUSTION PERCUSSIVE TOOLS

Aloyse Nicolas Wampach, Luxembourg, Luxembourg

Application April 21, 1953, Serial No. 350,136

Claims priority, application Luxembourg April 23, 1952

4 Claims. (Cl. 123—7)

The invention relates to portative internal combustion 15 percussion tools, and it has for its object an improved ramming tool of this type, in which a single piston performs the suction of the explosive mixture, the ramming and the exhaust of the waste gases.

According to my invention, I provide a portable ramming tool of the type referred to, in which the suction of the explosive mixture, the ramming stroke and the evacuation of the exhaust gases are carried out by a single piston the recoil of which is caused by a spring under tension housed inside a tubular percussion bar. The suction stroke of the said piston is carried into effect by means of a push-rod fixed to the yoke carrying the handles, which push-rod is provided with a bore through which the combustion chamber communicates with the atmosphere when the said push-rod is in its highest position.

The characteristic features of the apparatus according to the invention will become apparent in the course of the description which follows, with reference to the appended drawings which represent as an example a preferred embodiment of the invention. In these drawings:

Fig. 1 is a vertical axial section of the ramming tool;
Fig. 2 is a plan;

Fig. 3 is a sectional elevation, on a larger scale, of the locking mechanism of the push-rod.

In apparatus of the type referred to, that are known hitherto, the recoil of the piston is obtained by means of a spring in compression; the present invention resides principally in the substitution of a spring in tension housed inside the percussion bar, instead of the spring in compression.

As shown in Fig. 1, the ramming tool according to the invention consists in a body 21 the lower portion of which is a base containing the fuel tank 20 and the evaporative device 26, while the upper portion constitutes the cylinder in which reciprocates the piston 1 which is separate from a percussion bar 2 on which is secured the foot 14 constituting the ram, which this piston actuates through the intermediary of a sliding rod 6 independent from the said piston.

The arrangement of the spring for effecting the recoil of the piston 1 comprises a spring 5 under tension adapted to push the piston upwards by means of the sliding rod 6. The spring 5 is anchored at the top of the percussion bar 2 by means of a pin 5a, and its lower end is secured to a plug 7 against which presses the lower end of the sliding rod 6.

The handle bars are fixed to a yoke 8 to which is secured the push-bar 3, which is formed of two parts, the upper one of which is bored axially to receive the end of the lower part, of lesser diameter, held in the said axial bore by a bolt 4b and actuated by the compression spring 4a.

The push-rod 3 is constructed in two parts 3 and 4 in order to prevent, if the operator should inadvertently push down the operating yoke 8, and consequently the push-rod, before the piston 1 has been completely pushed back

2

against the cylinder head 16 by the sliding rod 6 under the thrust of the spring 5, the piston 1 from descending prematurely and injecting an insufficient quantity of explosive mixture, so that the force of impact of the ram 14 would be diminished.

This risk is removed by the arrangement just described, shown in greater detail in Fig. 3 on an enlarged scale. In the highest position of the yoke 8, the spring-controlled catch 9 slides under the surface 10 of the lower end of the push-rod 3 and maintains this latter rod in the position shown in Fig. 3 until the lower part 4 of the push-rod, pushed upwards by the piston 1 in its recoil stroke, forces back the catch 9, this action being facilitated by a bevel provided under the catch 9, which bevel is engaged by a corresponding bevel, parallel thereto, provided on the portion 4 of the push-rod. The catch 9 is provided with a slot in which passes the bolt 9a which guides it and retains it in position.

Owing to the construction of the push-rod in two parts, another great advantage is obtained, namely that, when the recoil of the piston 1 takes place, the two parts 3 and 4 slide inside each other and close the orifices 11 which put in communication the combustion chamber 22 with the atmosphere. After the remaining burnt gases from a previous explosion have in this way been evacuated, the piston 1 is sent down again and the suction is ensured thereby along the whole of its length.

A spring 12 under tension is also provided to effect the recoil of the foot 14 of the ramming tool. To this end, the percussion bar 2 is bored along its whole length and the tension spring 12 is anchored to the pin 13, solid with the foot 14, as shown in Fig. 1.

The ignition magneto (Fig. 2) is mounted in a known manner on the head 16 and is connected by the cable 17 to the sparking plug 18. Its circuit-breaker lever is actuated by an adjustable finger 19 mounted on the yoke 8.

The liquid fuel is stored in the tank 20 in the lower portion of the body 21, the explosive mixture is injected into the combustion chamber 22 by the descending piston through the pipes 23 and the admission valve 24. An adjustable valve 25, provided on the pipe 23, is provided for the adjustment of the secondary air. The liquid fuel evaporates along the surface of wicks 26 which are suspended and fixed on a circular metallic plate 27. The fuel is introduced by the opening 28 adapted to be closed by an adjustable plate 29 allowing primary air to pass and circulate between the wicks, the gaseous mixture proceeding along the pipe 23. The exhaust port for the burnt gases is shown at 30; 31 is a bolt enabling the tension of the spring 12 to be adjusted. In the foot of the ramming tool are disposed india-rubber rings 32 adapted to absorb the vibrations of the ram.

In operation, when the push-rod 3 is moved downwards by means of the yoke 8, the piston 1 moves downwards, pushing down the sliding rod 6 which slides inside the percussion bar 2. During this descent, a mixture of air and fuel is injected into the combustion chamber, in the manner described above, this mixture being ignited by an electric spark at the sparking plug 18, fed by the high voltage current from the magneto 15 when the finger 19 breaks the contact with the circuit-breaker lever of the magneto, during the descent of the yoke 8.

The effect of the explosion is to throw upwards the whole body of the ramming tool. During this instantaneous throw of the body, the piston is pushed down, together with the percussion bar 2 until the upper face of the piston uncovers the exhaust orifice 30 and almost the whole of the burnt gases has escaped through this orifice. The spring 5 is stretched at the same time.

As soon as the body of the ramming tool has left the ground, the foot 14, solid with the percussion bar 2, slides out of the body and remains suspended, separated

from the body. However, the tension spring 12 having been considerably stretched during this upward throw, immediately brings back the foot and the percussion bar before the body falls back on the ground and exerts its thumping action.

At the same time, the spring 5 brings back the piston 1 towards the cylinder head 16 and evacuates, as described above, the remaining burnt gases through the orifices 11 of the part 4 of the push-rod 3. In this manner the combustion chamber has become empty so as to cause the automatic descent of the yoke, of the push-rod and of the piston, during the fall of the body of the ramming tool, thereby causing a new aspiration of explosive mixture with a new subsequent explosion, so that the working cycle of the ramming tool is repeated.

What I claim is:

1. In a portable internal combustion ramming tool, a body, a tank for liquid fuel in the lower part of the said body, means for vaporising the said fuel in the lower part of the said body, a cylinder in the upper part of the said body, a piston in the said cylinder, a combustion chamber at the top of the said cylinder, over the said piston, a passage from the said vaporising means to the said combustion chamber, for an explosive mixture, means for exploding the said explosive mixture, an exhaust for the burnt gases, a percussion bar adapted to slide vertically in the said body, said percussion bar being bored along its whole length, a ram connected to the lower end of the said percussion bar, a helical spring housed within the said percussion bar and secured thereto at the top thereof, the other, lower end of the said spring being secured to a plug member adapted to slide inside the said percussion bar, a sliding tubular rod pressing at its upper end against and underneath the said piston and at its lower end resting on the said plug member and means for actuating the said piston.

2. A portable internal combustion ramming tool, as claimed in claim 1, wherein said means for actuating the piston comprise a push-rod slidably mounted on the upper portion of the said body, a yoke to which the said push-rod is secured, handles on the said yoke, the said push-rod being constituted by two co-axial parts, the lower one having its upper portion of reduced diameter engaging a corresponding bore in the upper part in which bore it is slidably held by means of a bolt under control of a compression spring, an axial passage in the lower part of the push-rod, a port putting the said passage in communication with the combustion chamber, a second port putting the said passage in communication with the atmosphere, said second port being covered when the lower part of the said push-rod penetrates into the bore of the upper part thereof.

3. A portable internal combustion ramming tool, as claimed in claim 1, wherein said means for actuating the piston comprise a push-rod slidably mounted on the upper portion of the said body, a yoke to which the said push-rod is secured, handles on the said yoke, the said push-rod being constituted by two co-axial telescopic parts under spring control, a spring controlled catch adapted to lock the upper part of the said push-rod and the said yoke in their highest position and means for pushing the said catch out of action when the piston is at the top of its recoil stroke, said latter means comprising co-engaging bevels on said catch and on the lower part of the said push-rod, respectively.

4. In a portable internal combustion ramming tool, as claimed in claim 1, a helical spring in the lower portion of the bore of the percussion bar, secured at one end to the said body and at the other end to the said ram.
